(57) **CLAIM**

The ornamental design for a male communication connector of an automation device, as shown and described.

DESCRIPTION

FIG. 1 is a perspective view of a male communication connector of an automation device showing our new design; FIG. 2 is a front elevational view thereof; FIG. 3 is a left side elevational view thereof; FIG. 4 is a right side elevational view thereof; FIG. 5 is top plan view thereof; and, FIG. 6 is a bottom plan view thereof.

In these drawings, the solid lines illustrate the claimed ornamental design, whereas the broken lines illustrate environmental features that form no part of the claimed ornamental design.
